Atty.

UNITED STATES PATENT OFFICE.

JOHN F. MEYER, OF CHICAGO, ILLINOIS.

CARD-VENDING MACHINE.

Application filed July 14, 1921. Serial No. 484,554.

To all whom it may concern:

Be it known that I, JOHN F. MEYER, a citizen of the United States, residing at Chicago, in the county of Cook and State of Illinois, have invented certain new and useful Improvements in Card-Vending Machines, of which the following is a specification.

This invention relates to vending machines and its object is primarily to prevent operation of the machine except through the medium of a proper coin and to insure correct operation of the machine when the predetermined coin has been properly inserted therein and the delivery mechanism operated.

A further object of the invention is to prevent the latch device of the coin controlled delivery apparatus from becoming displaced and to preserve said latch device constantly in operative position.

And a further object of the invention is to provide a simple means for securing the glass front of the vending machine cabinet rigidly in position thereon and at the same time permit this glass front and the advertising card held in place thereby to be readily removed for changing the card.

In the accompanying drawings I have illustrated the invention embodied in a machine for vending cards, such as picture cards and fortune cards, and referring thereto

Fig. 1 is a vertical sectional view of a vending machine embodying the invention;

Fig. 2 is a sectional view illustrating the coin controlled delivery mechanism in rearward position after being operated through the medium of a coin and ready to deliver a card from the bottom of the stack upon forward return movement of the slide bar.

Fig. 3 is a horizontal sectional view on the line 3—3 of Fig. 1.

Fig. 4 is a detail, transverse sectional view on the line 4—4 of Fig. 3.

Fig. 5 is a rear elevation of the lower part of the machine with the back plate removed.

Fig. 6 is a perspective view of a delivery slide which forms a part of my improved vending machine, and

Fig. 7 is a perspective view of a base bar which also forms a part of my improved vending machine.

Referring to the drawings the invention

comprises a suitable cabinet 6 having a magazine compartment 7 and adapted to contain a stack of cards 8 with a weight 9 on the top thereof, and a money compartment 10 having a removable door 11 provided with a suitable lock 12. A back plate 13 is adapted to be removably secured in the cabinet and is provided with a tongue 14 which engages a groove 15 in the bottom 16 of the cabinet, and with a lock 17 which engages the top 18 of the cabinet. The money compartment 10 is provided with a top 19 which extends from side to side and from front to back of the cabinet, and this top forms a support for the coin controlled delivery mechanism.

A delivery slide or push bar 20 is arranged to slide back and forth on a base bar 21 which is mounted on a base 22 and which has its rear end 23 bent down at the rear end of the base 22 and secured thereto by screws 23'. The base is secured rigidly on the top support 19 by a screw 24 which is exposed at the front of the machine and a bolt 25 passing through the base 22 and the top 19 and equipped with a wing nut 25'. By removing the screw 24 and the bolt 25 the base 22 with the entire coin controlled mechanism, one or more units thereof, may be removed for repair or replacement.

This wing nut 25' is located within the coinbox 10 and can be reached only after both the back 13 and door 11 have been removed. In practice the dealer, at whose establishment the machine is installed, is provided with a key to the back 13 to enable him to refill the magazine 7 with cards, while the owner of the machine retains the key to the door 11. Consequently by placing the wing nut 25' within the coin compartment, it is made impossible for a dishonest dealer to remove the base and coin controlled mechanism and then shake the coins out through the passage 19'.

The base bar 21 has a keeper plate 26 rigidly secured thereto and a latch 27 is pivotally or loosely mounted at 27' on the keeper plate so that its free end may have a limited up and down movement through an opening 26' in the keeper plate. The forward end of the latch is provided with a downwardly projecting hook 28 and at a point between this hook and the pivot connection 27' the latch is provided with a projection 29. The delivery slide has an opening 20' of sufficient size to receive the coin

which will operate the delivery mechanism and when the coin is inserted in this opening 20' it will rest upon the base bar 21, and the latter has an opening 21' therein 5 through which the coin carried back by the delivery slide may fall through an opening 22' in the base 22 and an opening 19' in the top support 19. The hook 28 and the projection 29 on the latch are arranged to 10 operate in a slot 30 in the delivery bar extending rearward from the coin opening 20', and provided with two cross pieces 30'-30'' located adjacent the coin opening (Fig. 2). The base bar is provided with a guide slot 15 31 and a guide screw 32 is secured in the delivery slide and projects through the slot 31 to cooperate with said slot for guiding the delivery slide in its back and forth movement. A delivery finger 33 is mounted 20 on the rear end of the delivery slide 20 and constitutes, in effect, a rigid part thereof. The rear edge 33' of this delivery finger is bent over and forwardly to form a sufficient projection to engage the rear edge of 25 the bottom card in the stack 8 when the delivery slide has been properly pushed to its rearmost position. The stack of cards is supported on a support 34 and on forward movement of the delivery slide the finger 30 will push the bottom card forwardly through the slot 35 and on to the table 36 which is rigidly mounted on the base 22. To insure that only one card will be 35 pushed through the delivery slot 35 I provide a gauge in the form of a plate 50 having slots 51 therein through which screws 52 pass to adjustably secure the gauge at just the proper distance from the table 36, which of course, is dependent upon the thickness of the cards to be vended. 40

The delivery slide may be pushed back without introduction of the coin but in such case rearward movement of the slide is limited by the engagement of the hook 28 with the cross bar 30'. The latch is held by a spring arm 37 (Fig. 3) in position for operative engagement with the cross bars, and lugs 38-38' are struck up from the keeper plate on opposite sides of the latch to retain it in 45 operative registration with the slot 30. Another lug 39 is also struck up from the keeper plate and the spring arm 37 is retained in operative engagement with the latch between the lugs 38' and 39. If a coin 50 is inserted in the opening 20' upon the base bar and the delivery slide is pushed rearward it will carry the coin along supported on the base bar until the coin engages the projection 29 of the latch, whereupon the 55 latch will be lifted sufficiently to cause the hook 28 to clear both of the cross bars 30'-30''. The coin is retained in place within the opening 20' and upon the base bar to support the latch until the delivery 60 bar has completed its rearward movement,

at which time the edge 33' of the delivery finger is positioned back of the rear edge of the bottom card in the stack and the coin opening 20' is registered with the opening 21' in the base bar permitting the coin to 70 drop through the openings 22' and 19' into the compartment 10. On the return or forward movement of the delivery slide the bottom card is ejected sufficiently from the machine to permit the purchaser to remove 75 it from the table 36.

I prefer to provide two cross bars 30' and 30'' so that if the hook should, for any reason, fail to engage the first cross bar 30' it may still engage the second cross bar 30'' 80 and thus guard against misuse of the machine. For instance, if a perforated washer was substituted for the proper coin, it would, when the slide was pushed back, act on the projection 29 and raise the hook 28 85 out of the path of the cross bar 30', but the projection would drop into the perforation in the washer in time for the hook 28 to catch the cross bar 30'' thereby preventing the slide from proceeding far enough to the 90 rear to effect the delivery of a card.

It is customary in machines of this kind to provide a glass front 40 for holding an advertising, or show card 41 therein. To permit the glass front to be easily and 95 readily removed for changing the card I support the glass front and the card on a ledge 42, forming part of the cabinet, and provided with a bead 42' to engage the lower edge of the glass front. The top of 100 the cabinet is provided with a groove 43 to receive the upper edge of the glass and this groove is of sufficient depth to permit the glass to be lifted to clear the bead 42'. For locking the glass in place I provide a screw 105 44 which is secured in the top of the cabinet and projects through the slot 43 above the glass front to prevent the glass front from being lifted to clear the bead 42'. This is a simple construction and arrangement of 110 parts which permits changing the card without opening the cabinet or any part of the mechanism.

My invention is simple in construction, it can be easily made in a strong and substantial manner by stamping the parts from sheet metal and it insures accuracy of operation and is proof against fraudulent operation. The removability of the entire delivery mechanism without taking the machine apart or necessitating the removal of the card supply is important because it is convenient to assemble the parts in units and permits removal of the delivery mechanism whenever it is required for repair or replacement with the least amount of mechanical skill. 120

I have described the invention as embodied in a machine for vending cards but it will readily be understood that it can be 125 130

embodied in machines for vending chewing gum or any other articles to which it can be adapted.

It is desirable, of course, that the delivery mechanism should only be operated by a coin of predetermined size for which the coin opening 20' in the delivery slide is made, and to prevent operation of the mechanism by smaller coins the coin opening 21' in the base bar is continued forward in the form of a somewhat narrow extension 21" which will permit a coin smaller than the predetermined coin to fall through whereas the predetermined coin will slide upon the base bar above the side edges of the extension.

I am aware that changes in the form, proportion and arrangement of parts may be made without departing from the spirit and without sacrificing any of the advantages of the invention and I reserve the right to make all such changes as fairly fall within the scope of the following claims.

25 I claim:

1. In a vending machine, a magazine for articles to be vended, a door for closing the magazine, a coin compartment closed by the said magazine door, a second door for closing the coin compartment only, a coin controlled delivery mechanism, a means for detachably securing said delivery mechanism to said coin compartment, said securing

means being controlled from within said coin compartment.

35

2. In a vending machine, a magazine for articles to be vended, a door for closing the magazine, a second compartment closed by said magazine door, a second door for closing said second compartment only, a coin controlled delivery mechanism, and a means for detachably securing said delivery mechanism to said second compartment, said securing means being controlled from within said second compartment.

45

3. In a vending machine, a magazine for articles to be vended, a door for closing the magazine, a coin compartment closed by said magazine door, a second door for closing the coin compartment only, a coin controlled delivery mechanism, a bolt for detachably securing said delivery mechanism to said coin compartment, and a nut threadedly engaging said bolt and disposed within said coin compartment.

55

4. In a vending machine, a coin compartment, a second compartment, vending mechanism in said second compartment, means for securing said vending mechanism to said coin compartment, said securing means being controlled from within said coin compartment, a door to close said coin compartment and a second door covering said first named door and closing said second compartment.

JOHN F. MEYER.
